UNITED STATES PATENT OFFICE

2,506,469

WINDOW VENTILATOR

Mae M. Rones, Brooklyn, N. Y., assignor of ninety
per cent to David Seidel, Brooklyn, N. Y.

Application September 19, 1946, Serial No. 697,951

4 Claims. (Cl. 98—96)

1

This invention relates to a combined ventilator and screen, attachable to windows and adapted to control the air flow into the room and at the same time exclude rain, snow and insects.

An object of this invention is the provision in a ventilator of the character described, of a frame which may be secured to a window sash and which carries a series of closely spaced louvers, and a covering panel detachably mounted upon the said frame and adjustable thereon to regulate the flow of air into a room.

Another object of this invention is the particular arrangement of the louvers to permit the entrance of air into the room while at the same time excluding the admission of rain, snow and insects, while keeping the window locked.

A further object of this invention is the inclusion therein of transparent louvers and closure panel which are constructed and arranged to permit outside light to enter the room at all times.

A still further object of this invention is the provision of an organization in which the constituent elements are so arranged structurally and functionally as to assure improved results with materials and members which may be manufactured at reasonable cost, may be easily assembled and which will be efficient in operation with minimum wear to the parts.

This invention possesses other objects and features of advantage, some of which, with the foregoing, will be set forth in the following description and in the claims wherein parts will be identified by specific names for convenience, but they are intended to be as generic in their application to similar parts as the art will permit. In the accompanying drawings there has been illustrated the best embodiment of the invention known to me, but such embodiment is to be regarded as typical only of many possible embodiments, and the invention is not to be limited thereto.

The novel features considered characteristic of my invention are set forth with particularity in the appended claims. The invention itself, however, both as to its organization and its method of operation, together with additional objects and advantages thereof, will best be understood from the following description of a specific embodiment when read in connection with the accompanying drawings, in which:

Figure 1 is a perspective view of the ventilator minus the closing and regulating panel.

Figure 2 is an end elevational view, partly in section, of the ventilator and shows the closing and regulating panel attached.

2

Figure 3 is a sectional plan view of the ventilator and shows a fragment of a window casing and sash to which the ventilator is attached.

Figure 4 is an isometric view of the regulating and closing panel.

Figure 5 is an enlarged fragmentary detail, which will be hereinafter described.

Figure 6 is a detail showing a means for locking the closing and regulating panel in a fixed position, and

Figure 7 is a front elevational view showing the device attached within a window sash.

Referring in detail to the parts, 11 designates a frame having upper and lower supporting brackets 12 and 13 respectively, over which a regulating and closing panel 14 is adapted to be suspended. Slots 15 and 16 are formed in the said closing and regulating panel 14, which are adapted to engage over the said brackets 12 and 13 respectively, to hold the said panel in place.

The frame 11 is provided with closely spaced and very thin louvers 17, arranged to form very narrow slotted openings 18, best illustrated in Figure 5. The said frame 11 may be mounted directly upon a window sash 19, as shown in Figure 3, or within a cutout portion of the glass pane 20, shown in Figures 2 and 7.

In the form shown in Figure 3, the frame may be attached to the sash by ordinary screws engaging through perforations 21 (see Figure 1), and into the sash 19. In the form shown in Figures 2 and 7, where attachment is made to the glass 20, a clip (see Figure 2), having an outside member 22 and an attached inside clamping member 23, forms an inner groove 24, to receive the frame 11, and an outer groove 25, to hold the said frame 11 within the cutout portion of the glass pane 20. The outside member 22 and the inside clamping plate 23 (Fig. 2) are adapted to form a holding frame which extends around the frame 11 and inside of the cut-out portion of the pane 20, with the tongue and groove joint 24 adapted to hold the said holding frame upon the pane 20 and in turn hold the frame 11 in place.

The aforesaid upper brackets 12 are formed with inner and outer notches 26 and 27 respectively, and the lower brackets 13 are formed with inner and outer notches 28 and 29 respectively, 50 within which the said panel 14 engages.

When the ventilator is mounted within a cutout portion of the window pane or upon the sash without the said regulating and closing panel, a maximum amount of outside air may enter the room through the openings 18, between the

louvers 17, and the extreme narrowness of the said openings 18 prevents the entrance therethrough of insects, and the arrangement of the louvers 17 will prevent the entrance of rain or snow.

To deflect the current of air entering the room through the louvers, the regulating panel 14 is suspended in the notches 27 and 29, formed in the supporting brackets 12 and 13 respectively. The air flow will then be diverted around the sides, top and bottom of the said regulating panel 14, as indicated by the arrows in Figure 2. The admission of air, however, may be entirely shut off by moving and suspending the said closing and regulating panel 14, in the notches 28 and 26, upon the brackets 12 and 13 respectively, as shown in Figure 3.

A locking clip 30, which may be rotatably attached to the frame 11, and which may engage through a slot 31 in the said closing and regulating panel 14, is provided as a means to prevent the displacement of the said closing and regulating panel 14.

The entire device, including the frame carrying the louvers and the closing and regulating panel, is preferably made of transparent plastic or of any other suitable transparent material.

Obviously, the device may be varied in size to fit either a part of a window sash or a part of a complete window, or it may be made large enough to fit the entire window opening.

I claim:

1. A ventilator comprising a frame secured to a window sash, the glass pane of which is removed or partly cut away, a series of closely spaced

louvers in said frame, upper and lower brackets upon said frame, and a panel member having upper and lower perforations therein adapted to engage over the said upper and lower brackets.

5. A ventilator as defined in claim 1, in which the said cut away portion of the said pane is rimmed by a clip member adapted to secure and hold the said frame carrying said louvers in position upon and within the said cut out portion 10 of the said pane.

6. The device as set forth in claim 1, wherein the said louvers and said closing and regulating panel are made of transparent material.

7. The device as set forth in claim 1, wherein 15 the supporting brackets are provided with a plurality of notches to adjustably hold the said closing and regulating panel.

MAE M. RONES.
